UNITED STATES PATENT OFFICE.

MORRIS H. KRONSON, OF BROOKLYN, NEW YORK.

FUR-TREATING MACHINE.

Application filed November 3, 1925. Serial No. 66,538.

My invention relates to a machine for treating pelts having the natural coating, hereinafter termed the fur.

The object of my invention is to produce a machine which will prepare the fur with a high finish.

My machine has a number of rotatable cylinders, so positioned that a conveyer belt carrying the pelts with their furry side up, may successively present the fur to the action of these cylinders. One or more of these cylinders is covered with bristles. At least one of these cylinders is heated so as to iron the fur and to give it a high lustre at the same time.

The preferred form of my invention is illustrated in the annexed drawing which forms a part of this application. I would, however, have it understood that various modifications and changes may be made without departure from the true spirit and scope of my invention.

Fig. 1 is an elevational left side view of the machine embodying my invention.

Fig. 2 is a right side view of same machine.

Fig. 3 is a fractional side view, showing sectionally, the fur treating elements of my machine.

Fig. 4 is a fractional top view of the elements shown in Fig. 3.

An endless conveyer belt 10, extending from feed or entrance platform 11 to discharge end 12, moves the pelts (which are placed on the belt in front of the feed platform with their furry sides up) between feed rolls 13 and 14. At least one of these rolls is spring-pressed. Spring 15 is shown pressing feed roll 13 down but either or both rolls may be spring-pressed.

After passing through the feed rolls, the belt moves over guide roll 16 and comes into contact with a cylindrical brush 17. This brush has a comparatively stiff set of bristles attached to its circumferential surface. The bristles are ordinarily of stiff steel wire but of course I do not confine myself to any particular type of bristle. The pelt is withdrawn from brush 17 by guide roll 18 which is circumferentially grooved at regular intervals. The pelt is brought again under the action of brush 17 by passing around a drum 19. Drum 19 which serves as a guide

member or guide roller is rotated by frictional contact with the conveyer belt 10. 55

The fur now comes into contact with a second and smaller cylindrical brush 20. The bristles used on this brush are finer and less stiff than are those used on brush 17. The bristles on the brushes 17 and 20 may be arranged uniformly as on ordinary rotary brushes or in helical groups as shown so as to give a more diverse action to the fur. After being brushed by brush 20 the fur passes between drum 19 and guide roller 21. 60 65 This roller is corrugated so as to offer a greater surface contact to the fur.

The fur is maintained in contact with the conveyer belt from roller 16 to roller 21 by means of guide wires 22 attached to brackets 23, 24 which in turn are attached to the frame of the machine. 70

The fur now passes around drum 19 until it is pressed between ironing roll 25, which is heated, and the drum 19. There the fur is subjected to an ironing action which also gives the fur a lustre. A roll 26 may cause the fur to be temporarily withdrawn from the ironing roll 25 but it returns to the ironing roll 25 and receives another heat treatment before the belt moves the fur on to the discharge end 12 where the pelts are taken off the conveyer belt 10 by an operator or are allowed to fall into a container. 75 80

The conveyer may have one or more flaps 27 under which a small portion of the front end of the pelt may be placed. This flap prevents the fur from slipping while being brushed and ironed. 85

Guide roll 16 is supported by a bracket 28 which may be adjusted up and down at any desired distance from brush 17 and held in place by bolt 29. An alternative method is to have roller 16 held similarly to roller 18. This is held in an adjustable position by means of a pivoted and slotted arm 30. 90 95

The machine receives its power through shaft 31 which obtains its power from an external source. In Fig. 2 shaft 31 is supposed to rotate in a clockwise direction. Pulleys 32, 33 and belt 34 (shown in dotted lines) connect the shaft 31 to the brush 17. Arrows 35 show the direction of the motion of the belt which is in opposition to the motion of the active faces of the brushes 17 100 and 20. 105

Sprocket wheels 36, 37 and chain 38 connect counter-shaft 39 to main shaft 31, and counter-shaft 40 is connected to counter-shaft 39 by chain 41 and its sprocket wheels.

5 Counter-shaft 40 through chain 42 turns a roll 43 which frictionally engages the conveyer belt and causes it to move as shown by the arrows. Shaft 40 also revolves ironing roll 25 through chain or belt 44.

10 Ironing roll 25 may be rotated in the same direction as the conveyer belt by removing chain 44 and connecting cylinder 43 and the ironing roll 25 by means of pulleys and a belt twisted 180°. The ironing roll is supported

15 as shown by two pivoted arms 45 so that the ironing roll may be swung clear of the belt as shown by the dotted lines.

Referring to Fig. 1 showing the left hand side of my machine, shaft 39 turns the brush 20 by belt 46 and also turns shaft 47 through chain 48. Shaft 47 by chain 49 rotates guide rolls 18 and 21 against the motion of the conveyer belt 10.

Under the feed or entrance platform 11 25 roller 50 holds the conveyer belt 10 in such a position as to best receive the pelts from the feed platform. Roller 51 is held by arm 52 and spring 53 so as to keep the conveyer belt at the desired tension.

30 The ironing roll 25 may be heated by any convenient means. For the purpose of illustration I have shown it as being heated by a gas burner placed within the roll, but I do not confine myself to any particular 35 method of heating.

Under actual test this machine has treated furs and has given them a beautiful smoothness and lustre. In fact it is possible to treat very rough and unattractive pelts by this 40 method and produce a fur having the appearance and feel of fine expensive furs.

I claim:

1. A machine adaptable for brushing and ironing furs on the pelt having a rotatable 45 heated member, a conveyer belt and means for causing furs on said conveyer belt to be temporarily withdrawn from and returned to contact with said heating member.

2. A pelt treating machine comprising a 50 guide, a drum, a brush rotatable to press toward said guide and drum, a second brush pressing toward said drum, a conveyer passing over said guide, under said first mentioned brush and over said drum, and a 55 heating iron for finishing the pelts after they have been brushed.

3. A pelt treating machine comprising a 60 guide, a drum, a brush rotatable to press toward said guide and drum, a second brush pressing toward said drum, a conveyer passing over said guide, under said first mentioned brush and over said drum, wires co-acting with said conveyer to guide the pelts past said brushes and a heating iron for finishing the pelts after they have been brushed.

4. A cylindrical guide member, a cylindrical heating iron adjacent thereto, a conveyer belt passing over said guide member and beneath said iron, and a brush for treating pelts on the conveyer while on said guide. 70

5. A cylindrical guide member, a cylindrical heating iron adjacent thereto, a conveyer belt passing over said guide member and beneath said iron, and a brush for treating pelts on the conveyer while on said guide 71 and means for retracting said iron.

6. A machine for treating pelts which comprises a conveyer, two spaced guide rollers, a brush for engaging said conveyer adjacent both rollers, and an intermediate adjustable guide roller between said spaced guide rollers. 80

7. In a pelt treating machine, a rotating drum, a brush, a conveyer travelling between said brush and drum and a corrugated roller 81 coacting with pelts while they are on said conveyer and it is on said drum.

8. In a pelt treating machine, a rotating drum, a conveyer travelling around said drum, two brushes coacting with said drum and rotating so that the active surface of the brushes travels in the opposite direction to the active surface of said conveyer and guide wires extending around one face of said drum between said conveyor and said 89 brushes.

9. In a pelt treating machine, a rotating drum, a conveyer travelling around said drum, and two brushes coacting with said drum and rotating so that the active surface of the brushes travels in the opposite direction to the active surface of said conveyer guide wires coacting with said conveyor past said brushes and a heated polishing iron 101 coacting with the pelts on said conveyer beyond said drum.

10. A pelt treating machine comprising a guide, a drum, a rotatable brush to press toward said guide and drum, a conveyor belt, means for retracting said conveyor belt 1 from said brush and guide wires coacting with said conveyor belt to guide pelts on said conveyor past said rotatable brush.

11. In a pelt treating machine, a rotatable guide, a rotatable drum, a conveyor belt, traveling on said guide and drum, a rotatable brush adjacent said belt, means for retracting the surface of said conveyor belt from said brush and a corrugated roller 11 adapted to press against said pelts when said pelts pass between said corrugated roller and said rotatable drum.

12. In a pelt treating machine a conveyor belt, a cylindrical drum, two rotatable brushes pressing toward said conveyor belt while said conveyor belt is in contact with said drum, guide wires coacting with said conveyor belt to guide pelts between said brushes and said drum, and a corrugated roller adapted to press against said furs 11

while said furs are passing around a part of said drum.

13. In a machine for treating furry pelts a feed platform, feed rolls adjacent to said feed platform, a rotating member, a plurality of substantially rigid members extending outwardly from said rotating member

and adapted to strike against the lay of the fur, a curved member adapted to be heated internally and means for guiding the pelt into contact with said rigid members on said rotating member and past said heated member. ¹⁰

MORRIS H. KRONSON.
